UNITED STATES PATENT OFFICE.

HENRY J. HANCOCK, OF NEW YORK, N. Y., ASSIGNOR OF ONE-HALF TO
WILLIAM S. JESSUP, OF SAME PLACE.

DESIGN FOR A SEWING-MACHINE FRAME.

SPECIFICATION forming part of Design No. 33,585, dated November 20, 1900.

Application filed October 25, 1900. Serial No. 34,396. Term of patent 14 years.

To all whom it may concern:

Be it known that I, HENRY J. HANCOCK, a citizen of the United States, residing at New York, in the county and State of New York, have invented and produced a new and original Design for a Sewing-Machine Frame, of which the following is a specification, reference being had to the accompanying drawings, forming part thereof.

10 Figure 1 is a side elevation of a sewing-machine frame, showing my new design. Fig. 2 is an end view of the same.

As shown in the drawings, the leading or material feature of my design consists of a

15 curved standard 5, having the circular perforated part 6, the bottom arm 7, which is enlarged centrally and formed into an upwardly-projecting part 8, carrying the outwardly-projecting plate 9, and the part 8 ends with

20 the acorn-shaped piece 10 and two curved side pieces 11 11. The enlarged central part is also formed into a downwardly-projecting part 12, carrying the plate 13, which projects outwardly, parallel with the plate 9, and the

25 part 12 ends with an ornamentation similar to the ending of the part 8. The central part of the arm 7 I cut away to form a diamond-

shaped opening 14, the sides of which are inwardly curved. The arm 7 is further provided with the projections 15 15 and with the upwardly-projected extension 16, provided with the two arms 17 and 18, which end with the plates 19 and 20, respectively. The standard 5 also carries a top arm 21, carrying the cross-head 22, the lower end of which is provided with the outwardly-projecting plate 23 and the upper end is provided with the bearing 24, while the standard 5 is provided with a similar bearing 25, at the top thereof. The arm 21 is also provided with the projections 26 and 27.

Having described my invention, what I claim as new, and desire to secure by Letters Patent, is—

The design for a sewing-machine frame, as herein shown and described.

In testimony whereof I have signed my name to this specification in the presence of two subscribing witnesses.

HENRY J. HANCOCK.
